UNITED STATES PATENT OFFICE.

ISIDOR KITSEE, OF PHILADELPHIA, PENNSYLVANIA, ASSIGNOR OF ONE-HALF TO WILLIAM J. LATTA, OF PHILADELPHIA, PENNSYLVANIA.

TELEGRAPHIC TRANSMITTING DEVICE.

No. 821,043.

Specification of Letters Patent.

Patented May 22, 1906.

Application filed May 27, 1905, Serial No. 262,635.

To all whom it may concern:

Be it known that I, ISIDOR KITSEE, of the city and county of Philadelphia, State of Pennsylvania, have invented certain new and useful Improvements in Telegraphic Transmitting Devices, of which the following is a specification.

My invention relates to an improvement in telegraphic transmitting devices.

Its object is to send with the aid of a common transmitting-key connected to the devices embodying my invention true reversals over the line of transmission.

In Letters Patent No. 777,259, granted to me December 13, 1904, I have pointed out the necessity of telegraphing with true reversals over long-distance lines or cables, and to the transmission over such lines this, my invention, has special reference.

Referring to the drawings, Figure 1 is a top plan view of a device adapted to change the polarity or direction of the flow of impulses transmitted over the line. Fig. 2 is a side elevation of the same, partially in section, to illustrate part of the mechanism of the device in detail. Fig. 3 is a diagrammatic view showing the device in connection with the transmitting-key and showing the electrical connections to the transmitting batteries and the line.

A is an electromagnetic device actuating the mechanical part of the pole-changing device. A' is the movable lever thereof. To this lever is secured the escapement B, working into the toothed wheel C, keyed to the shaft D. To this shaft is also keyed the contact-wheel E, provided with the contact-points or teeth e. In operative relation to these points or teeth e are the contact-brushes F and F', secured to the non-conducting support F². The teeth of the gear-wheel G, keyed to the same shaft as the contact-wheel, mesh with the teeth of the gear-wheel H, keyed to the shaft I, and the teeth of the gear-wheel J, keyed to the shaft K, mesh with the teeth of the wheel h, keyed to the shaft I. Revolving in unison with the wheel J is the ratchet-wheel J' in operative relation to the ratchet J². On the shaft K is loosely mounted the drum L, provided with the cord M', having attached thereto the weight M. This device is provided with the binding-posts a and a', securing the terminals

of the coils of the electromagnetic device A, and the binding-posts a² and a³ being the terminals of the brushes F and F', respectively. The binding-post a⁴ is in electrical connection through the metallic frame with the contact-wheel E. N is the transmitting-key proper, comprising the lever N', the stationary contact N², and the intermediate conductor N³.

The electrical connection of this device is as follows: The lever N' of the key N is connected, through wire 1, with the binding-post a⁴. Brush F is connected, through wire 2, binding-post a², and wire 5, with the positive pole of the source of current O, joined through wire 6 with the positive pole of the source of current O', the negative pole of which is connected, through wire 4, binding-post a³, and wire 3, with the brush F'. Both sources O and O' are connected at their junction through wire 7 with the ground Z. To the stationary contact N² of the key N is connected, through wire 8 and binding-post a, one terminal of the coil of the electromagnetic device A, and the other terminal of said coil is connected, through binding-post a' and wire 9, with one pole, here shown as the negative pole of the source of current P, the other pole of which is connected, through wire 10, with the intermediate conductor N³ of the key N. The contact-point N² is also in electrical contact through wire 11 with the line of transmission.

Before describing the operation of the device it is necessary to state that the teeth e of the contact-wheel E are arranged in relation to the brushes F and F' in a manner so that when the brush F touches one of these teeth the brush F' is out of contact with said teeth, and, vice versa, if the brush F' touches one of said teeth the brush F is out of contact with same. It is also necessary to state that the number of teeth or contact-points of the contact-wheel E has to coincide with the number of teeth in the escapement-wheel C, and it may be stated that the movable part A' of the electromagnetic device A may be so adjusted that through its downward stroke the escapement B will be brought in relation to the teeth of the wheel C, so as to allow for each downward stroke the escape of one of the teeth of said wheel.

The operation of the device embodying my invention is as follows: Normally—that is, when the key is not depressed—the circuit

including the coil of electromagnetic device A is open. So, also, will the circuit of the batteries O and O' be interrupted, for the reason that no matter if the brush F or F' touches one tooth *e* of the wheel E, yet this circuit will always be interrupted as long as the lever N' is out of contact with the line of transmission. To send an impulse over the line, the operator depresses the lever N' of the key 10 N. Through this depression the intermediate piece N³ will first be brought in contact with N², thereby closing the circuit, including the electromagnetic device A. The armature A' of this device will be brought downward, and this operation will result therein that the escapement B will allow one tooth of the wheel C to escape. It is now supposed that formerly the brush F was resting on one of the teeth *e*. This brush will now be brought 20 out of contact with this tooth, and the brush F' will be brought in contact with one or the other of said teeth. Through a further depression of the lever N' of the key this lever will come in contact with the point N² and 25 will through same make electrical connection with the line of transmission grounded at the distant point. A circuit will thereby be established comprising the battery O', and the current will flow from the positive pole of this 30 battery, junction-wire 6, wire 7, ground Z, through distant ground connected to the line of transmission, wire 11, contact N², intermediate conductor N³, lever N', wire 1, binding-post a⁴, metallic part of the frame, shaft 35 D, wheel E, teeth *e*, brush F', wire 3, binding-post a⁵, wire 4, back to the negative pole of the battery O'. The impulse transmitted, therefore, will flow in the direction of the unfeathered arrow through the line of transmission. It is supposed that the operator 40 now transmits a second impulse over the line. Through the manipulation of the lever N' the intermediate conductor N³ will again come first in contact with the point N², thereby 45 closing again the circuit, including the coil of electromagnetic device A. The armature A', which through the opening of the key has again resumed its upward position, will now again be drawn downward, through which 50 action the escapement B will be operated in a manner to again release one tooth of the wheel C, thereby revolving the wheel E a space equal to one tooth. This movement of the wheel E will bring out of contact the brush F' from the tooth *e*, where it formerly 55 rested, and will bring the brush F in contact with the adjacent tooth *e* of the same wheel. In now further depressing the lever N' this lever in coming in electric contact with the 60 point N² will again close a circuit including the line of transmission; but this time the circuit will embrace the battery O, and the current will flow from the positive pole of this 65 battery, through wire 5, binding-post a², wire 2, brush F, tooth *e* of the wheel E, shaft

D, metallic frame and binding-post a⁴, wire 1, lever N', intermediate conductor N³, contact N², line of transmission, distant ground, ground Z, wire 7, junction-wire 6, back to the negative pole of the battery O. This impulse will therefore flow in the direction of the feathered arrow through the line of transmission—that is, in a direction opposite to the preceding impulse. In the further operation of this key every succeeding depression 70 will send one impulse over the line; but each impulse will be of a polarity opposite to the polarity of the preceding impulse, and if the key is always depressed for the same unit of time it is obvious that true reversals are transmitted over the line. 80

The different gearing is necessary in this instrument for the reason that otherwise too frequent winding-up of the same would be necessary, and the weight M is necessary for 85 the reason that otherwise the escapement-wheel C would not revolve. In the working of this device it has also to be borne in mind that the escapement B does not perform any other function than to allow the revolving of 90 the wheel C, actuated by the weight M.

I have here described the mechanical construction I prefer and have found to be efficient in actual working over telegraph-lines; but details of such device may be changed 95 in accordance with requirements without departing from the scope of my invention.

Instead of closing the line-circuit through the key the line-circuit can be closed through the downward stroke of the armature A' of 100 the electromagnetic device A. In this case the wire 1 may be connected to one part of the electromagnetic device and the wire 11 to the other part, so, for instance, the wire 1 to the adjustable contact-screw A² of the armature A', and the wire 11 to the conducting part A³ of said device, as is indicated in Fig. 2 by the dotted lines. 105

Having now described my invention, what I claim as new, and desire to secure by Letters Patent, is—

1. In telegraphy, a transmitting device embracing the key proper, a pole-changing device, said pole-changing device embracing an electromagnet, an escapement carried by 115 the armature of said electromagnet, a train of wheels, operatively connected to said escapement, a contact-wheel carried by the shaft of one of said wheels, two brushes in operative relation to said contact-wheel, a 120 source of current for each of said contact-brushes, both sources electrically connected with each other and grounded at their junction, and driving means to revolve said train of wheels. 125

2. In telegraphy, a pole-changing transmitting device embracing a key proper, an electromagnetic device connected to said key, a pole-changing contact-wheel, electrical connection for same, two sources of 130

current grounded at their junction, and means to connect alternately one or the other of said sources to said contact-wheel, driving means to revolve said contact-wheel, and means to make inoperative said driving means, said means depending on the energizing of the electromagnet through the operation of the key proper.

3. In a device of the class described, a contact-wheel, two brushes for said contact-wheel, one source of current connected with the positive pole of one of said brushes, a second source connected with the negative pole of the second of said brushes, both sources

grounded, driving means to revolve said contact-wheel, an electromagnet and means carried by said electromagnet to make inoperative said driving means, a key adapted to make inoperative the means carried by said electromagnet.

In testimony whereof I hereby sign my name, in the presence of two subscribing witnesses, this 26th day of May, A. D. 1905.

ISIDOR KITSEE.
